OPERATION CONTROL INTERLOCKING MECHANISM FOR TYPEWRITERS OR LIKE MACHINES

John F. Kloski, Hartford, and William H. Kupper,
West Hartford, Conn., assignors to Royal Type-
writer Company, Inc., New York, N. Y., a cor-
poration of New York

Application February 6, 1951, Serial No. 209,619

17 Claims. (Cl. 197—107)

1

This invention relates to operation control interlocking mechanism for typewriters or like machines, and more particularly to interlocking mechanism for preventing simultaneous actuation of finger keys or like members for controlling such operations as tabular stop setting, tabulation, carriage return, and back spacing, and for preventing the operation of such control members when an operation such as a returning or tabulating movement of the carriage is taking place.

An object of the invention is to provide a new and improved interlocking mechanism having parts cooperable respectively with several control keys or levers in such a way that when one of the control keys or levers is in depressed or operated position, the others are blocked or restrained so that they cannot be operated.

Another object of the invention is to provide interlocking mechanism of the kind referred to including two independently movable blocking slides so mounted and related to the control keys or levers as to require exertion of a minimum effort for being moved to their several blocking positions, thus lightening the "touch" required to operate the keys or levers.

Another object of the invention is to provide interlocking mechanism of the general character referred to in combination with new and improved means for rendering the mechanism operative for blocking one or more of the keys or levers when an operation such as a carriage returning or tabulating operation is being performed.

Further objects of the invention will become apparent from a reading of the following description, the appended claims, and the accompanying drawings, in which:

Figure 1 is a fragmentary fore and aft sectional view of a power operated typewriter embodying the invention, with the parts shown in their normal positions and with certain parts shown in elevation;

Figure 2 is a view similar to Figure 1 but with certain parts omitted, and certain of the parts illustrated being shown in operated positions;

Figure 3 is a view similar to Figure 1 but with certain parts omitted, drawn on an enlarged scale, and with some of the parts shown in operated positions;

Figure 4 is a fragmentary horizontal sectional view on the line 4—4 of Figure 1;

Figure 5 is a fragmentary vertical sectional view from end to end of the machine, on the line 5—5 of Figure 1, showing key blocking slides and related parts;

Figure 6 is a view similar to Figure 5 with certain parts omitted and other parts being shown in positions different from the position shown in Figure 5;

Figure 7 is a view similar to Figure 6 but with

2

certain of the parts shown in still other positions;

Figure 8 is a fragmentary vertical sectional view on the line 8—8 of Figure 4 drawn on an enlarged scale and with some parts shown in elevation;

Figure 9 is a fragmentary vertical sectional view on the line 9—9 of Figure 4, drawn on an enlarged scale and with some parts shown in elevation; and

Figure 10 is a horizontal sectional view on the line 10—10 of Figure 5.

The invention is illustrated as being embodied in a power operated typewriter, portions of a fixed frame of which are generally designated A. The typewriter includes electrically powered actuating or driving mechanism generally designated B and which is basically similar to but embodying improvements in the mechanism disclosed in the copending application of William H. Kupper, Serial No. 6,066, filed February 3, 1948, now Patent No. 2,567,945, issued September 18, 1951. The mechanism B supplies power for operating a tabulating mechanism for forward movement of a link instrumentality, a front portion of which is shown at C, and the rear end of which is connected to tabulating mechanism not shown herein but which may be, for example, of the kind disclosed in the copending application of William H. Kupper, Serial No. 180,579, filed August 21, 1950, now Patent No. 2,620,057, issued December 2, 1952. Transmission of movement from the power mechanism B to the tabulating link instrumentality C for moving the latter forwardly is controlled by a tabulating key C' pivoted at 1 on a frame cross bar 2.

The mechanism B is also adapted to operate a carriage return mechanism by effecting forward movement of a link instrumentality, a front portion of which is shown at D and the rear portion of which is connected to carriage return mechanism which may be similar to the mechanism disclosed in the copending application of Henry J. Hart, Serial No. 21,476, filed April 16, 1948, now Patent No. 2,567,937, issued September 18, 1951.

45 The operation of the link D by the mechanism B is controlled by either of two carriage return keys D'—D' pivoted at 1 on the cross bar 2, and connected to work as a unit by a rod 3 intervening between and rigidly connecting the keys D'—D'.

50 The typewriter shown is also equipped with a back spacing key E' adapted to control the mechanism B for operating back spacing mechanism, not shown herein, but which may be of the kind disclosed in the copending application of John F. Kloski and William H. Kupper, Serial No. 115,542, filed September 13, 1949, now Patent No. 2,577,467, issued December 4, 1951.

55 As shown in Figures 1 and 2, a typewriter constructed in accordance with the present invention may include a further link instrumentality,

a front end portion of which is shown at F and the rear end portion of which may be connected to tabular stop setting mechanism not shown herein but which may be of any suitable kind such, for example, as that shown in the patent to Myers and Handley, No. 1,892,071, of December 27, 1932. The link F may be operated directly—that is to say, manually—by a tabular set key F' rather than through the intermediary of the power mechanism B.

Typewriters embodying the invention also are equipped with the usual complement of type bars and typing keys which may be operable by power mechanism of the kind disclosed in the aforementioned copending Kupper application Serial No. 6,066, now Patent No. 2,567,745, issued September 18, 1951.

The mechanism B for operating the link instrumentalities C and D and others, not shown, includes a driving element, which operates continuously, and controllable driving connections, which normally are inoperative or ineffective, but which may be conditioned by the operator selectively to effect operative driving connection between the continuously moving driving member and the pull links C and D. The driver is constituted by a continuously rotating element, more particularly a toothed snatch roll or bar 4, which may be of known form, and which is adapted to be driven in the direction of the arrow a in Figure 1 by any suitable means, but preferably by an electric motor (not shown).

The means for transmitting drive from the driver 4 to the tabulator operating link C includes an actuator 5 which extends fore and aft of the typewriter and above the member 4. The actuator 5 is pivoted as at 6 to a lever 7 at a point off-set relatively to the pivotal mounting 8 of the lever on a fixed frame cross bar 9. The upper end of the lever 7 is pivoted at 7a to the front end portion of the link C. The actuator has a forwardly extending part 10 projecting under an abutment or guide plate 11 mounted on the cross bar 2, to extend parallel to the snatch roll 4. A spring 12, interposed between the front end of the actuator 5 and a fixed anchor (not shown), yieldably urges the actuator to rock clockwise, and thus normally maintains the actuator in the position shown in Figure 1 with its front end part 10 bearing against the abutment or guide plate 11. Another abutment 13 is disposed below the abutment 11, and is slotted to receive and guide the lower extremity of the actuator part 10 for sliding movements.

In order to apply a power impulse to the link C, the actuator 5 is operatively but indirectly connected to the driving member 4, the actuator itself never engaging the driving member. Mechanism for bringing about the operative connection of the actuator element 5 to the member 4, includes an interponent pawl or coupler 14, pivoted as at 15 on the actuator. A spring 16, anchored to the actuator 5 and connected to the pawl part 14, biases or urges the latter to rock clockwise so as to move its nose 14a into transient engagement with the snatch roll 4. Normally, the pawl is maintained out of engagement with the snatch roll by the restraining action of a control element or trigger 17 which is pivoted as at 18 on the actuator 5. In the normal position of the trigger, its rear end 19 engages a holding surface 20 on the pawl so as to prevent the spring 16 from rocking the pawl element 14 into drive-transmitting engagement with the driving member 4. The pawl 14 is formed with

an inclined resetter cam face 21 which is located just below the holding surface 20, and which is acted upon by the trigger for rocking the pawl counterclockwise, and thus resetting it in normal, 5 inoperative position.

Operator controlled means is provided for bringing about operative driving connection between the driver 4 and the actuator 5. This means includes the manually operable tabular key device C' normally held in its upper position engaging a cushion stop 22. The forward end of the key C' is guided by a slotted comb guide 22a.

The tabular key C' has an upward projection 15 23 disposed behind an arm 24 of an operating lever 25, pivoted as at 26 on a frame-mounted cross bar 27. The lever 25 has another arm 28 on which a limber dog or flipper 29 is pivoted at 30. A spring 29a urges the limber dog 29 to rock clockwise to retain it yieldably in its normal position of rest against a limit stop 30a. The dog 29 can swing counterclockwise from the position shown in Figure 3, but cannot move clockwise from this position. A returning spring 25 31, interposed between the tabular key C' and a short arm 32 on the lever 25, yieldably holds the lever 25 and the tabular key C' in their normal positions. Normally the lower end of the limber dog 29 overlies a contact ear 33 on the actuator 5.

In operation, when the tabular key C' is depressed, the lever 25 is rocked clockwise to cause the flipper 29 to push the actuator 5 downwardly to an initial extent sufficient to bring the trigger 35 17 into engagement with the abutment 13. This causes the trigger to be rocked clockwise about its pivot 18, so as to release the pawl 14, which is then moved by the spring 16 into engagement with the snatch roll 4. The snatch roll then drives the pawl 14 and actuator 5 as a unit so as to rock the lever 7 and operate the link C. When the pawl 14 is cast off from engagement with the snatch roll 4, the spring 12 lifts the actuator 5 to bring the trigger 17 into engagement with the upper, 40 trigger-resetting abutment 11. This causes the trigger 17 to be rocked counterclockwise so as to move its end 19 against the resetting cam face 21 of the pawl 14, thereby restoring the latter to its inactive position. At the end of a tabulating operation, the parts of the mechanism B will be returned toward their normal positions by a spring 45 34 interposed between a rearwardly extending arm 35 on the lever 7 and the lower part of a bracket 36 fixed to the frame cross bar 9. A tabular normalizing spring (not shown herein but shown at 68 in the aforementioned Kupper application, Serial No. 180,579, now Patent No. 2,620,057, issued December 2, 1952), assists the spring 34 to return the parts to normal positions after the tabulating operation has been completed. The lever 7 is provided with a heel 37 engageable with the upper part of the bracket 36 for limiting the return movement of the lever 7 and the connected parts to their normal positions.

Means are provided for adjusting or varying the amount of driving impulse generated by the power mechanism B. This variation or adjustment is effected by variably limiting the extent to which the actuator pawl nose 14a enters a tooth interspace on the snatch roll 4 under the urge of the spring 16 when the restraint of the trigger 17 on the pawl 14 is discontinued. In the form shown, the actuator 5 is provided with a downwardly extending stop element or finger 38 which is disposed in front of and normally out of contact with

a downwardly extending stop part, heel, or finger 39 on the pawl 14. When the pawl 14 is rocked clockwise by the spring 16 so as to move the pawl nose 14a into a snatch roll tooth interspace, the pawl stop 39 moves toward the actuator stop 38, which may be so positioned as to be engaged by the stop 39 to arrest rocking of the pawl 14 before the tooth 14a moves to the root of the snatch roll tooth interspace. By variably positioning one of the stops 38, 39, e.g., by bending the stop 38 towards or away from the stop 39, the extent to which the pawl tooth 14a enters the tooth interspace can be varied. Consequently, the angle through which the snatch roll rotates while in contact with the pawl, which determines the amount of driving of the pawl 14 and actuator 5 by the snatch roll 4, can be varied. Any suitable means or construction may be provided for adjusting one of the stops 38, 39 relatively to the other, but in the preferred construction the stop 38 is formed integrally with the actuator 5 so as to be bendable toward or away from the stop 39.

In typewriters or like machines in which all or some of the instrumentalities to be operated, e.g., type bars, carriage return mechanism, tabulating mechanism, and escapement mechanism are operated by power, it may be desirable to provide means for varying collectively the extent of driving of the several actuator pawls corresponding to the pawl 14 and associated with the other mechanisms referred to. This may be accomplished by providing a knock off bar 40 mounted on the main frame so as to extend under the front ends of all of the actuators corresponding to the actuator 5 shown in Figures 1 and 3. Any suitable means (not shown), may be provided for adjustably tilting or otherwise variably positioning the knock off bar 40 so that it will be engaged by the lower ends of the actuators to control the timing of disengagement of the associated actuator pawls from the snatch roll.

Normally, the parts for operating the tabulating mechanism are in the positions shown in Figure 1. In order to initiate a tabulating operation, the tabulating key C' is depressed to the position shown in Figure 3 so as to rock the lever 25 clockwise, push the actuator 25 downwardly, and release the trigger 17 so as to permit the spring 16 to move the pawl 14 into engagement with the snatch roll 4. The consequent forward movement of the actuator 5 will rock the lever 1 counter-clockwise to the position shown in Figure 3 so as to pull forwardly on the tabulating link C. When the link C has been moved to its forward position, it will be latched so as to be retained in its operated position until the tabulating operation—that is, the leftward movement of the carriage—has been completed, and will then be unlatched and returned to its normal or retracted position. The latching and unlatching mechanism associated with the tabulating link C is fully disclosed in the aforementioned Kupper application Serial No. 180,579, now Patent No. 2,620,057, issued December 2, 1952.

The mechanism B also includes connections between the snatch roll 4 and the carriage return link D operable under the control of the carriage return keys D'—D' for pulling the link D forwardly so as to effect operation of the carriage return mechanism in the manner disclosed in the aforesaid copending Hart application Serial No. 21,476, now Patent No. 2,567,937, issued September 18, 1951. These connections are similar to those described above with reference to the operation of the tabulating link C, and only certain of

the parts need be shown and described. Those of the parts constituting these connections for operating the carriage return mechanism D which are illustrated are designated by reference characters the same as those applied to corresponding parts of the connections for operating the tabulating link C, but are distinguished in that the characters applied to the parts for operating the carriage return link D are primed. Thus, the parts for actuating the carriage return link D include an actuator 5', a lever 7', and a pawl 14' corresponding to the actuator 5, the lever 7, and the pawl 14.

The carriage return link D corresponds to the pull link 98 disclosed in the copending Hart application Serial No. 21,476, now Patent No. 2,567,937, issued September 18, 1951, with the exception that the link D is adapted to be latched or held in its forward or operated position until the carriage return operation has been completed, whereas, in the construction disclosed in the copending Hart application, the link 98 is permitted to return immediately after the beginning of a carriage return movement. In substance, the carriage return link D shown in the present application may be latched or held in its operated position during the performance of a carriage return operation by connecting the pull link 98 disclosed in the copending application directly to its associated latch lever arm 88 instead of through the one-way operable latch actuator 101 shown in the Hart application.

In operation, when a carriage key D' is depressed, the associated pawl 14' and actuator 5' are driven forwardly by the snatch roll 4 to rock the lever 7' counterclockwise as viewed in Figure 9 so as to pull the carriage return link D forwardly and permit it to be latched in its moved position until the end of the carriage return operation, when the link D will be permitted to return to its non-actuated position.

The back spacing key E' is adapted to control mechanism not disclosed herein for transmitting power from the driver 4 to the carriage to effect incremental back spacing movement of the latter. The back spacing mechanism operable under the control of the key E' may, as previously stated, be of the kind disclosed in the copending Kloski and Kupper application Serial No. 115,542, now Patent No. 2,577,467, issued December 4, 1951.

The tabular set key F' is formed with slots 41—41 through which extend headed studs 42—42 secured to a vertical stationary frame plate 43 so as to mount the key F' for horizontal sliding movements. Secured to the key F' is a headed stud 44 which extends through a slot 45 in the upper end of a lever 46 pivoted to rock on a headed stud 47 secured to the frame plate 43. The lower end of the lever 46 has lost motion pivotal connection at 48 to the front end of the link F, the rear end of which is connected to tabular stop setting mechanism not shown but which may be substantially of the kind disclosed in the Myers and Handley patent, No. 1,892,071, previously referred to. The arrangement is such that, when the tabular set key F' is pushed rearwardly from its Figure 1 position to its Figure 2 position, the link F will be pulled forwardly to set the tabular stop in a well known manner.

The mechanism described so far is, to a large extent, either known in the prior art or disclosed in the copending applications referred to above. The present invention relates more particularly to interlocking mechanism for preventing the conjoint operation of certain of the keys C', D',

E', and F', and for preventing the operation of certain of these keys when a protracted operation such as a tabulating operation or a carriage returning operation is being performed, the invention relating also to the combination of the interlocking mechanism with certain of the parts described above.

Interlocking mechanism

Normally ineffective key actuated blocking mechanism operable independently of the power mechanism B and the instrumentalities which it operates is provided for preventing depression of more than one of certain of the spaced or deployed selectively operable keys C', D', E', and F' at one time. The key actuated interlocking mechanism includes a unitary blocking slide 49 formed with slots 50 and 51 through which respectively extend studs 52 and 53 secured to the frame 43, the arrangement being such that the slide 49 can have limited shifting movement transversely with respect to the typewriter frame. The slide 49 is formed with vertically extending or upstanding fingers 56, 57, and 58, the finger 56 having a cam edge 56^a disposable under the back spacing key E', the finger 57 having an oppositely inclined cam edge 57^a disposable under the carriage return key D', and the finger 58 having an inclined cam edge 58^a disposable under the front arm 60^a of an interlocking lever arm 60 pivoted at 61 on the frame cross bar 2 and held in normal position by a spring 61'.

The spacing of the fingers 56, 57, and 58 with respect to each other and with respect to the keys D' and E' and the interlocking lever arm 60^a is such that certain of the fingers block certain of the related parts D', E', and 60^a according to the shifted position of the slide 49. In the form shown, the contiguous vertical edges of the fingers 57 and 58 are spaced from each other a distance substantially equal to the center-to-center distance between the key lever D' and the interlocking arm 60^a. Thus, when the slide 49 is in the position shown in Figures 5 and 6, the fingers 56 and 58 respectively block movement of the key E' and the interlocking lever arm 60^a. When the slide 49 is in the position shown in Figure 7, the finger 57 will block depression of the carriage return keys D'. If the slide 49 is in the position shown in Figure 5, downward movement of either the back spacing key E' or the interlocking lever arm 60^a will, through the cooperation of the downwardly moved part and the associated cam edge 56^a or 58^a, move the slide 49 to its Figure 7 position. Similarly, if the slide 49 should be in the position shown in Figure 7 and if the carriage return key D' should be depressed, it will engage the cam surface 57^a and shift the slide 49 leftwardly to the position shown in Figures 5 and 6.

A second blocking slide 62 is formed with slots 54 and 55 through which extend respectively the stud 53 previously referred to and a stud 63 secured to the slide 49 so as to mount the slide 62 for transverse shifting independently of the slide 49. The slide 62 is formed with a single vertically extending finger 65 somewhat wider than the fingers 56, 57, and 58 and having oppositely inclined converging cam edge portions 65^a, 65^b at its upper end. The slide 62 can occupy either of two positions, the first position being shown in Figure 5 and the second position being shown in each of Figures 6 and 7. When the slide is in the position shown in Figure 5, and is held there as by previous depression of the

tabulating key C', the slide cam edge 65^a is disposed under the carriage return key D' so as to prevent its being depressed. If, with the slide positioned as shown in Figure 5 but with the tabulating key C' in elevated or normal position, the carriage returning key D' is depressed, it will engage the cam edge 65^a so as to shift the slide 62 to the position shown in Figure 6, in which the cam edge 65^b will be disposed below the tabulating key C' so as to prevent its being depressed as long as the carriage returning key D' is in depressed position, preventing leftward movement of the slide 62.

The slides 49 and 62 are formed with interengageable parts which cooperate to effect shifting of one slide when the other slide is shifted by depression of one of the keys or the interlocking lever arm 60^a. In the form shown, the finger 55 of the slide 62 has its upper portion 55^c offset rearwardly as shown in Figures 1 and 3 so as to be disposed alongside and in the plane of movement of the finger 57 on the slide 49, the arrangement being such that the left edge of the finger part 55^c is engageable with the right edge of the finger 57. Thus, if the slide 49 is moved toward the right from its Figure 5 position, the right edge of the finger 57 will push against the left edge of the finger part 55^c of the slide 62 so as to shift the slide 62 toward the right together with the slide 49. Similarly, if the parts are in the positions shown in Figure 7, and the slide 62 is shifted to the left as by downward movement of the tabulating key C', the left edge of the finger part 55^c will push against the right edge of the finger 57 so as to move the slide 49 to the left to the position shown in Figures 5 and 6.

The interlocking lever element 66 is formed with a rearward and upward extension 66^b having an ear 66^c extending in front of a slide 66 formed with slots 67 through which extend headed studs 68 secured to the vertical stationary plate 43. A stud 69 secured to the slide 66 is disposed in front of the lower end of the lever 46 operable by the tabular set key F' as previously explained. When the key F' is depressed or moved toward the right from its normal position shown in Figure 1, the lever 46 is rocked clockwise, so that its lower end pushes against the stud 69 and moves the slide 66 toward the front of the machine, that is, toward the left as viewed in Figures 1 and 2. When neither one of the keys C', D' is in depressed position, the front end of the slide 66, moved forwardly by the lever 46, will press against the ear 66^c on the lever 60 and rock the latter counterclockwise as viewed in Figures 1 and 2 so as to move the interlocking arm 60^a from the position shown in Figures 5 and 6 to the position shown in dotted lines in Figure 7. In moving downwardly, the interlocking arm 60^a will engage the inclined cam edge 58^a of the finger 58 so as to move the slide 49 from the position shown in Figures 5 and 6 to the position shown in Figure 7. On the other hand, if either of the keys C', D' is in depressed position, so that the slide 49 is held in the position shown in Figures 5 and 6, the interlocking lever arm 60^a is blocked against downward movement by the finger 58, so that, in turn, the slide 66, lever 46, and tabular set key F' are blocked against operative movement.

The several conditions which may be met in normal operation of the typewriter and the interlocking functions performed in accordance with these conditions will be reviewed briefly. If

the keys are all in normal positions, and the slides 49 and 62 are in the positions shown in Figure 5, and the tabular set key F' is depressed, the lever 46 and slide 66 will operate through the one-way drive connection 66-60° to rock the interlocking lever 60 and move the interlocking lever arm 60a to the position shown in dotted lines in Figure 7, thus shifting the slides 49 and 62 to the positions shown in Figure 7. With the parts so positioned, the tabulating key C', which is intermediate the key lever D' and the lever 60, is blocked against operation by the finger 65, and the carriage returning key D' is blocked by the finger 57. The finger 56 will not block the back spacing key E' against depression, so that, conceivably, the tabular setting key F' and back spacing key E' could be operated simultaneously, but this could not result in damage to the machine.

If the keys should be in their normal positions and the slides 49 and 62 in the positions shown in Figure 7, depression of the tabulating key C' would shift the slides 49 and 62 to the positions shown in Figure 5, so that the finger 65 would prevent depression of the carriage returning key D', and the interlocking lever arm 60a would be restrained by the finger 58, consequently preventing depression of the tabular setting key F'. The finger 56 would prevent depression of the back spacing key E' so as to prevent conjoint operation of the tabulating mechanism and the back spacing mechanism, thereby avoiding damage which otherwise could be caused.

If the keys should be in their normal positions and the slides 49 and 62 in the positions shown in Figure 5, depression of the carriage return key D' would move the slide 62 to and retain it in the position shown in Figure 6, and would retain the slide 49 in the position shown in both Figure 5 and Figure 6. The finger 65 would be disposed under the tabulating key C' so as to prevent operation of the tabulating mechanism; the finger 56 would be disposed under the back spacing key E' so as to prevent operation of the back spacing mechanism; and the finger 58 would be disposed under the interlocking arm 60a of the lever 60 so as to prevent operation of the tabular setting key F' and the tabular setting mechanism.

If the keys should be in their normal positions and the slides 49 and 62 in the positions shown in Figure 5 when the back spacing key E' is depressed, the key E' would engage the cam surface 56a on the finger 56 so as to move the slide 49 and also the slide 62 to the positions shown in Figure 7. With the parts so positioned, the finger 57 will block the carriage returning key D' against depression; and the finger 65 will block the tabulating key C' against depression. The finger 58 will be disposed out of the path of the interlocking arm 60a, so that, conceivably, the tabular setting key F' could be operated conjointly with the back spacing key E', but, as previously stated, conjoint operation of these keys would not result in damage to the machine.

The interlocking mechanism described above is effective only when one of the key controlled movable lever members D', E', F', and 60 is operated. In accordance with the invention, co-operating mechanism is provided for preventing depression of any of the keys C', D', and F' when either the tabulating mechanism or the carriage return mechanism is in operation, even though the tabulating key C' or the carriage return key

D' has been restored to normal position before the completion of the attendant operation.

Mechanism for locking the keys C', D', and F' against operation when a tabulating operation is in progress in consequence of the link instrumentality C having been operated, and after the tabulating key C' has been restored to its normal position, includes a slide member 70 formed with slots 71-71 through which the studs 68-68 extend. The front end of the slide 70 is disposed immediately behind and normally is in engagement with the ear 60° on the interlocking lever 60. Fixed to the slide 70 adjacent its rear end is a pair of headed pins or studs 72-72 which extend through slots 73-73 formed in another slide member 74, which thereby is mounted for sliding movements on and with respect to the slide 70. A yieldable motion transmitting spring connection 75 is interposed between an ear 76 on the slide 74 and an ear 77 on the rear end of the slide 70 so as normally to retain the slides 70 and 74 in the relative positions shown in Figures 1 and 2. The rear end of the slide 74 is formed with a downturned portion 78 and a horizontally extending ear 79.

A shaft 80 is mounted to rock on the stationary plate 43 and a fixed frame part 81 shown in Figure 4. Fast with the shaft 80 is an arm 82 which extends upwardly in front of the ear 79 on the slide 74, the arm 82 being curved rearwardly and downwardly as at 83 and being provided with an ear 84 projecting horizontally across the rear end of the downturned end 78 of the slide 74.

Mechanism is provided for rocking the shaft 80 and the arm 82 counterclockwise from the position shown in Figures 1 and 2 to the position shown in Figure 3 when the tabulating link C is moved forwardly in response to depression of the tabulating key C'. In the form shown, the link C is provided with a pin 85 which extends behind an arm 86 fast with the shaft 80. The arrangement is such that, when the link C is moved forwardly to initiate a tabulating operation, the pin 85 will rock the arm 86, the shaft 80, and the arm 82 counterclockwise as viewed in the drawings. This will cause the ear 84 on the arm 82 to press against the rear end of the slide 74 so as to push the latter forwardly and, through the spring 75, to move the slide 70 also forwardly, so that its front end will push against the ear 60° and rock the interlocking lever 60 counterclockwise to the position shown in Figure 3, thus moving the interlocking lever arm 60a to the position shown in dotted lines in Figure 7. The slides 49 and 62 will thus be positioned as shown in Figure 7, so that the keys C' and D' will be blocked against operation in the manner previously described.

In order that the tabular setting key F' will be blocked against operation during the course of a tabulating operation, the slide 70 is equipped with a stop 87 which normally is disposed out of the path of a cooperating stop 88 on the lever 46, the stop 87, however, being adapted to be moved under or into the path of the stop 88 when the slide 70 is moved forwardly in the manner described above. When the stop 87 has been moved into the path of the stop 88, the parts will be in the relative positions shown in Figure 3, so that the lever 46 cannot be rocked effectively, and the tabular setting key F' consequently cannot be operatively depressed.

At the end of the tabulating operation, the link C is caused to return or move rearwardly, as explained in the aforementioned Kupper ap-

pllication, Serial No. 180,579, now Patent No. 2,620,057, issued December 2, 1952, thus retracting the pin 85 from the arm 86 and permitting the shaft 80, the arm 82, and the slides 74 and 70 to be returned to normal positions by a wrapped spring 89 anchored at its opposite ends respectively to the fixed frame part 81 and to an arm 90 secured to the shaft 80.

Mechanism for locking the keys C', D', and F' when the carriage return mechanism is in operation also includes the slides 70 and 74, the spring 75, the arm 82, and the shaft 80, the construction and operation of which have been described above. For operating these parts in response to operation of the carriage returning mechanism, an ear 91 is formed on the carriage return operating link D so as to extend behind the arm 90 securing to the shaft 80.

In operation, when the carriage returning link D is moved forwardly in response to depression of the key D', the ear 91 on the link D will press against the arm 90 so as to rock the latter, the shaft 80, and the arm 82 counterclockwise. As previously stated, such movement of the arm 82 will cause the slides 74 and 70 to be moved forwardly so as to rock the interlocking lever 60 to its Figure 3 position, and thus to position the interlocking arm 60^a as shown in dotted lines in Figure 7. As previously explained, such positioning of the interlocking arm 60^a will cause the blocking slides 49 and 62 to be located as shown in Figure 7, so that the tabulating key C' and the carriage returning key D' will be blocked against depression.

The stop 87 on the slide 70 also will have been moved to its Figure 3 position so as to prevent effective downward movement of the stop 88 on the lever 46, thus blocking the tabular setting key F' against operative movement.

If the tabulating key C' or the carriage returning key D' should be held down while a tabulating operation or a carriage returning operation is being performed, the slide 49 will be held in the position shown in Figures 5 and 6, with the finger 58 on the slide 49 positioned to block downward movement of the interlocking lever arm 60^a, consequently preventing rocking of the lever 60 and forward movement of the slide 70. No harm will be done when the tabulating link C or the carriage returning link D is moved forwardly with consequent rocking of the shaft 80 and forward movement of the slide 74, because the spring 75 will be held to permit the slide 70 to remain stationary although the slide 74 is moved forwardly.

The mechanism disclosed embodies the invention in its preferred form, but it is intended that the disclosure be illustrative rather than definitive of the invention.

We claim:

1. In a typewriter or like machine, three spaced key-controlled movable members; a blocking slide having two cam portions which are so spaced with respect to each other and with respect to two of said members that when a first of said cam portions is disposed in the path of a first of said two members a second of said cam portions is disposed out of the path of a second of said two members, and when said second of said cam portions is disposed in the path of said second of said members said first of said cam portions is disposed out of the path of said first of said members; means mounting said slide for shifting movement in the direction of spacing of said members and said cam portions, said first and second cam portions being so inclined that

when either one is engaged by the associated movable member said slide will be shifted to position the other cam portion in the path of the other movable member, the third of said members being operable concurrently with said first of said members without harmful effect; a third cam portion so positioned on said slide as to be disposed in the path of said third of said members when said first of said cam portions is disposed in the path of said first of said members, and to be disposed out of the path of said third of said members when said first of said cam portions is disposed out of the path of said first of said members, said third cam portion being so inclined that when it is engaged by said third of said members said slide will be shifted to position said second of said cam portions in the path of said second of said two members.

2. In a typewriter or like machine, three spaced key-controlled movable members; a unitary blocking slide having two oppositely inclined cam portions which are so spaced with respect to each other and with respect to two of said members that when a first of said cam portions is disposed in the path of a first of said two members a second of said cam portions is disposed out of the path of a second of said two members, and when said second of said cam portions is disposed in the path of said second of said members said first of said cam portions is disposed out of the path of said first of said members; means mounting said slide for shifting movement in the direction of spacing of said members and said cam portions, said first and second cam portions being so inclined that when either one is engaged by the associated movable member said slide will be shifted to position the other cam portion in the path of the other movable member, the third of said members being operable concurrently with said first of said members without harmful effect; a third cam portion so positioned on said slide as to be disposed in the path of said third of said members when said first of said cam portions is disposed in the path of said first of said members, and to be disposed out of the path of said third of said members when said first of said cam portions is disposed out of the path of said first of said members, said third cam portion being so inclined that when it is engaged by said third of said members said slide will be shifted to position said second of said cam portions in the path of said second of said two members.

3. In a typewriter or like machine, three depressible key-controlled levers, the first and third of said levers being operable concurrently without harmful effect but the second of said levers not being operable concurrently with either of said first and third levers without harmful effect; means mounting said levers in deployed relation; a unitary blocking slide; and means mounting said slide to extend under said levers in the direction of deployment thereof and for endwise shifting, said slide having three upstanding fingers so spaced with respect to each other and with respect to said levers that when the first and third of said fingers are disposed in the paths of the first and third of said levers the second of said fingers is disposed out of the path of the second of said levers, and when said second of said fingers is disposed in the path of said second of said levers said first and third of said fingers are disposed out of the paths of said first and third of said levers, said fingers having upper cam portions so relatively inclined that depression of either of said first and third of said levers

when its associated finger is disposed in its path and the second of said levers is in normal position will shift said slide to position said second of said fingers in the path of its associated lever, and depression of said second of said levers when its associated finger is disposed in its path and said first and third of said levers are in normal positions will shift said slide to position said first and third of said fingers in the paths of their respectively associated levers.

4. In a typewriter or like machine, a plurality of key-controlled movable members; means mounting said members in deployed relation; and interlocking means cooperable with three of said members including a first or intermediate member and second and third members flanking said first or intermediate member for preventing concurrent operation of two or all three of said three members, said interlocking means comprising a first blocking slide having two cam portions which are so spaced with respect to each other and with respect to said second and third members that when said slide is in a first position one of said cam portions is out of the path of said second member and the other of said cam portions is in the path of said third member, and when said slide is in a second position said other of said cam portions is out of the path of said third member and said one of said cam portions is in the path of said second member, said cam portions being so inclined that when either one is engaged by its associated member said slide will be shifted to position the other cam portion in the path of its associated member, a second blocking slide having oppositely inclined cam edges, one of said edges being disposed in the path of said second member when the other of said edges is disposed out of the path of said first member when said second slide is in a first position, and said other of said edges being disposed in the path of said first member when said one of said edges is disposed out of the path of said second member when said second slide is in a second position, means mounting said slides for independent sliding movement, and interengageable parts on said first and second slides for moving said second slide to its second position when said first slide is moved to its second position and for moving said first slide to its first position when said second slide is moved to its first position.

5. In a typewriter or like machine, first, second, and third spaced depressible key-controlled levers, the first lever being between the second and third levers, relatively close to the second lever, and relatively remote from the third lever, a first blocking slide having two upstanding fingers the contiguous vertical edges of which are spaced from each other a distance substantially equal to the center-to-center spacing of said second and third levers, the tops of said fingers having portions respectively inclined from said contiguous edges upwardly and away from said contiguous edges; a second blocking slide having an upstanding finger wider than the distance between adjacent vertical faces of said first and second levers, said last named finger having two inclined portions converging upwardly from its vertical side edges; and means mounting said slides under said levers for shifting in the direction of spacing of said levers by engagement of respective depressed ones of said levers with underlying inclined portions on said slides, said slides having interengageable parts for transmitting shifting movement from one slide to the other and vice versa.

6. In a power operated typewriter or like machine, a plurality of instrumentalities to be operated; a driving member; means including a plurality of selectively operable devices for effecting driving of selected ones of said instrumentalities by said driving member; and mechanism for preventing operation of said devices when one of said instrumentalities is in operated position in consequence of one of said devices having been operated, said mechanism comprising normally ineffective blocking means adapted to be rendered effective to block operating movement of said devices, a first member operable for rendering said blocking means effective, a second member operable by movement of the operated instrumentality to operated position, and a yieldable motion transmitting connection between said first and second members.

7. In a power operated typewriter or like machine, a plurality of instrumentalities to be operated; a driving member; means including a plurality of selectively operable devices for effecting driving of selected ones of said instrumentalities by said driving member; and mechanism for preventing operation of said devices when one of said instrumentalities is in operated position in consequence of one of said devices having been operated and for preventing operation of non-operated ones of said devices when another of said devices is in operated position, said mechanism comprising normally ineffective blocking means adapted to be rendered effective to block operating movement of said devices, a first member operable for rendering said blocking means effective, a second member operable by movement of the operated instrumentality to operated position, a yieldable motion transmitting connection between said first and second members, and means operable in response to operation of one of said devices for rendering said blocking means effective for blocking the other of said devices.

8. In a power operated typewriter or like machine, a plurality of instrumentalities to be operated; a driving member; means including a plurality of selectively operable devices for effecting driving of selected ones of said instrumentalities by said driving member; and mechanism for preventing operation of said devices when one of said instrumentalities is in operated position in consequence of one of said devices having been operated, said mechanism comprising normally ineffective blocking means adapted to be rendered effective to block operating movement of said devices, a first slide operable for rendering said blocking means effective, a second slide, means mounting said second slide for sliding movement with respect to and in the direction of operative sliding movement of said first slide, means operable by movement of the operated instrumentality to operated position for moving said second slide, and a yieldable motion transmitting spring connecting said slides.

9. In a power operated typewriter or like machine, a plurality of instrumentalities to be operated; a driving member; means including a plurality of selectively operable devices for effecting driving of selected ones of said instrumentalities by said driving member; and mechanism for preventing operation of said devices when one of said instrumentalities is in operated position in consequence of one of said devices having been operated, said mechanism comprising normally ineffective blocking means adapted to be rendered effective to block operating movement of said devices, a first slide

operable for rendering said blocking means effective, a second slide, means mounting said second slide for sliding movement with respect to and in the direction of operative sliding movement of said first slide, means operable by movement of the operated instrumentality to operated position for moving said second slide, a yieldable motion transmitting spring connecting said slides, and means for returning said slides to normal positions in response to return of the 10 operated instrumentality to normal position.

10. In a power operated typewriter or like machine, a plurality of instrumentalities to be operated; a driving member; means including a plurality of selectively operable devices for 15 effecting driving of selected ones of said instrumentalities by said driving member; and mechanism for preventing operation of said devices when one of said instrumentalities is in operated position in consequence of one of said devices having been operated, said mechanism comprising normally ineffective blocking means adapted to be rendered effective to block operating movement of said devices, a first slide operable for 20 rendering said blocking means effective, a second slide, pin-and-slot means mounting said second slide on and for sliding movement with respect to said first slide and in the direction of operative sliding movement of said first slide, means operable by movement of the operated instrumentality to operated position for moving said second slide, and a yieldable motion transmitting spring connecting said slides. 25

11. In a power operated typewriter or like machine, a plurality of instrumentalities to be operated; a driving member; means including a plurality of selectively operable devices for 30 effecting driving of selected ones of said instrumentalities by said driving member; and mechanism for preventing operation of said devices when one of said instrumentalities is in operated position in consequence of one of said devices having been operated and for preventing operation of non-operated ones of said devices when another of said devices is in operated position, said mechanism comprising normally ineffective blocking means adapted to be rendered effective to block operating movement of said devices, a first slide operable for 35 rendering said blocking means effective, a second slide, means mounting said second slide for sliding movement with respect to and in the direction of operative sliding movement of said first slide, means operable by movement of the operated instrumentality to operated position for moving said second slide, a yieldable motion transmitting spring connecting said slides, and means operable in response to 40 operation of one of said devices for rendering said blocking means effective for blocking the other of said devices. 45

12. In a power operated typewriter or like machine, a plurality of instrumentalities to be operated; a driving member; means including a plurality of selectively operable devices for 50 effecting driving of selected ones of said instrumentalities by said driving member; and mechanism for preventing operation of said devices when one of said instrumentalities is in operated position in consequence of one of said devices having been operated and for preventing operation of non-operated ones of said devices when another of said devices is in operated position, said mechanism comprising normally ineffective blocking means adapted to be rendered effective to block operating movement of said devices, a 55

first slide operable for rendering said blocking means effective, a second slide, pin-and-slot means mounting said second slide on and for sliding movement with respect to said first slide and in the direction of operative sliding movement of said first slide, means operable by movement of the operated instrumentality to operated position for moving said second slide, a yieldable motion transmitting spring connecting said slides, and means operable in response to operation of one of said devices for rendering said blocking means effective for blocking the other of said devices. 60

13. In a power operated typewriter or like machine, a plurality of instrumentalities to be operated; a driving member; means including a plurality of selectively operable devices for 65 effecting driving of selected ones of said instrumentalities by said driving member; and mechanism for preventing operation of said devices when one of said instrumentalities is in operated position in consequence of one of said devices having been operated, said mechanism comprising normally ineffective blocking means adapted to be rendered effective to block operating movement of said devices, a first slide operable for rendering said blocking means effective, a second slide, means mounting said second slide for sliding movement with respect to and in the direction of operative sliding movement of said first slide, a yieldable motion transmitting spring connecting said slides, a rockable shaft, a part operable by rocking of said shaft for moving said second slide to transmit force through said spring to move said first slide and to thus render said blocking means effective, and arms on said shaft cooperable respectively with said instrumentalities for rocking said shaft in response to movement of the operated instrumentality to operated position. 70

14. In a power operated typewriter or like machine, a plurality of instrumentalities to be operated; a driving member; means including a plurality of selectively operable devices for effecting driving of selected ones of said instrumentalities by said driving member; mechanism for preventing operation of said devices when one of said instrumentalities is in operated position in consequence of one of said devices having been operated and for preventing operation of non-operated ones of said devices when another of said devices is in operated position, said mechanism comprising normally ineffective blocking means adapted to be rendered effective by operating movement of one of said devices to block operating movement of the other of said devices, a first member movable from a normal position to an operated position only when said blocking means is ineffective for rendering said blocking means effective and being restrained against movement from said normal position by said blocking means when the latter has been rendered effective in consequence of operation of one of said devices, and a second member operable by movement of the operated instrumentality to operated position; a key for operating a further instrumentality; means including a one-way drive connection for transmitting movement from said key to said first member for moving the latter from its normal position when said blocking means has not previously been rendered effective and for preventing operation of said key when said blocking means has been rendered effective and said first member is thereby restrained against movement from its normal position. 75

sition; and a stop movable by operation of said second member from an inactive position to an active position in which it prevents operation of said key when said second member is in operated position.

15. In a power operated typewriter or like machine, a plurality of instrumentalities to be operated; a driving member; means including a plurality of selectively operable devices for effecting driving of selected ones of said instrumentalities by said driving member; mechanism for preventing operation of said devices when one of said instrumentalities is in operated position in consequence of one of said devices having been operated and for preventing operation of non-operated ones of said devices when another of said devices is in operated position, said mechanism comprising normally ineffective blocking means adapted to be rendered effective by operating movement of one of said devices to block operating movement of the other of said devices, a lever rockable from a normal position to an operated position only when said blocking means is ineffective for rendering said blocking means effective and being restrained against movement from said normal position by said blocking means when the latter has been rendered effective in consequence of operation of one of said devices, and a first slide operable by movement of the operated instrumentality to operated position for rocking said lever to operated position; a key for operating a further instrumentality; means including a second slide mounted to move independently of said first slide and providing a one-way drive connection for transmitting movement from said key to said lever for rocking the latter from its normal position when said lever is not restrained by said blocking means and for preventing operation of said key when said lever is restrained; a first stop movable by operation of said key; and a cooperating stop on said first slide normally positioned out of the operating path of said first stop but being movable into the path of said first stop by operation of said first slide for preventing operation of said key.

16. In a power operated typewriter or like machine, a plurality of instrumentalities to be operated; a driving member; means including a plurality of selectively operable devices for effecting driving of selected ones of said instrumentalities by said driving member; mechanism for preventing operation of said devices when one of said instrumentalities is in operated position in consequence of one of said devices having been operated and for preventing operation of non-operated ones of said devices when another of said devices is in operated position, said mechanism comprising normally ineffective blocking means adapted to be rendered effective by operating movement of one of said devices to block operating movement of the other of said devices, a lever rockable from a normal position to an operated position only when said blocking means is ineffective for rendering said blocking means effective and being restrained against movement from said normal position by said blocking means when the latter has been rendered effective in consequence of operation of one of said devices, a first slide operable for rocking said lever to operated position, a second slide operable by movement of the operated instrumentality to operated position, and a motion-transmitting spring connection between said first and second slides; a key for operating a further instrumentality; means including a third slide 75

mounted to move independently of said first and second slides and providing a one-way drive connection for transmitting movement from said key to said lever for rocking the latter from its normal position when said lever is not restrained by said blocking means and for preventing operation of said key when said lever is restrained; a first stop movable by operation of said key; and a cooperating stop on said first slide normally positioned out of the operating path of said first stop but being movable into the path of said first stop by operation of said first slide for preventing operation of said key.

17. In a power operated typewriter or like machine, a plurality of instrumentalities to be operated; a driving member; means including two keys for selectively effecting driving of selected ones of said instrumentalities by said driving member; a movable element; means including a yieldable motion transmitting connection for operating said element in response to movement of one of said instrumentalities to operated position; and interlocking means cooperative with said keys and with said movable element for preventing operation of said element and either of said keys when the other of said keys is in operated position, and for preventing operation of either of said keys when said element is in operated position, said interlocking means comprising a first blocking slide having two cam portions which are so spaced with respect to each other and with respect to one of said keys and said element that when said slide is in a first position one of said cam portions is out of the path of said one of said keys and the other of said cam portions is in the path of said element, and when said slide is in a second position said other of said cam portions is out of the path of said element and said one of said cam portions is in the path of said one of said keys, said cam portions being so inclined that when either one is engaged by its associated key or element said slide will be shifted to position the other of said cam portions in the path of its associated key or element, a second blocking slide having oppositely inclined cam edges, one of said cam edges being disposed in the path of said one of said keys when the other of said cam edges is disposed out of the path of the other of said keys when said second slide is in a first position, and said other of said cam edges being disposed in the path of said other of said keys when said one of said cam edges is disposed out of the path of said one of said keys when said second slide is in a second position, means mounting said slides for independent sliding movement, and interengageable parts on said first and second slides for moving said second slide to its second position when said first slide is moved to its second position and for moving said first slide to its first position when said second slide is moved to its first position.
